US0D1066847S

(12) **United States Design Patent** (10) **Patent No.:** **US D1,066,847 S**
(45) **Date of Patent:** **** Mar. 11, 2025**

(54) **HANDLE**

(71) Applicant: **The Libman Company**, Arcola, IL (US)

(72) Inventors: **Jon Franklin**, St. Joseph, IL (US); **Andrew D. Libman**, Champaign, IL (US); **Fernando de Jesus Santos**, Maceira Lra (PT)

(73) Assignee: **The Libman Company**, Arcola, IL (US)

(**) Term: **15 Years**

(21) Appl. No.: **29/895,088**

(22) Filed: **Jun. 16, 2023**

(51) LOC (15) Cl. **07-05**

(52) U.S. Cl. **D32/35**
USPC ....

(58) **Field of Classification Search**

USPC D8/300, 307, 310, 311; D32/25, 31, 32, D32/34, 39

CPC A46B 5/0095; A46B 5/02; A46B 5/021

(57) **CLAIM**

The ornamental design for a handle, as shown and described.

DESCRIPTION

FIG. 1 is a front, right, top perspective view of the claimed design for a handle;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines immediately adjacent to the shaded area depict boundaries of the claimed design and form no part thereof. The broken lines showing the remainder of the handle depict environmental structure and form no part of the claimed design.

1 Claim, 4 Drawing Sheets
